UNITED STATES PATENT OFFICE.

ALONZO ALDRICH, OF BELOIT, WISCONSIN.

PAPER-MAKING MACHINE.

Application filed October 18, 1922, Serial No. 595,258. Renewed May 23, 1927.

My invention relates to paper making machines, and particularly to Fourdrinier machines.

One of the objects of the invention is to permit and arrange for the vibration of the wire without vibrating the entire table.

Another object of the invention is to provide simple, practical and effective means for accomplishing this purpose.

10 In the accompanying drawings Fig. 1 is a side elevation of the breast roll end of a Fourdrinier machine embodying my present invention;

15 Fig. 2 is a cross section taken on line 2—2 in Fig. 1;

Fig. 3 is an end view of a table; and

Fig. 4 is a cross section taken on line 4—4 in Fig. 3.

Referring to the drawings, I show a portion of a Fourdrinier machine comprising side frame pieces 1—1, preferably channel iron in form. Table rolls 2—2 are also shown, a breast roll 3 and a wire 4 traveling over the table rolls 2—2 and breast roll 3.

25 The table rolls are so mounted that they may be vibrated or shaken sidewise so as to shake or vibrate the wire and thereby give a good formation to the paper, and this mounting permits the table rolls to be vibrated in this way without vibrating the entire table. As one form of construction, I show the table rolls mounted on longitudinally extended side members or rails 5—5, and these in turn mounted on a series of 30 vibratory or swinging supports 6—6 whose lower ends are secured to the side members 1—1 by brackets 7—7. The vibratory members 6—6 are preferably of some flexible material, as for example, oak or other wood, 40 permitting their upward ends to vibrate so as to vibrate or shake the side supports or rails 5—5 and table rolls 2—2.

For shaking or vibrating the side members 5—5 I show a series of eccentrics 8—8 45 whose straps 9—9 are connected with eccentric rods 10 which in turn are connected with the side members 5—5. The eccentrics 8—8 are mounted on a rotary driving shaft 11 which extends along the side of the machine, being mounted in bearings 12—12 supported by brackets 13—13 secured to side frame member 1, whereby rotation of shaft 11 operates eccentrics 8—8 and vibrates or shakes rolls 2 and wire 4.

55 The breast roll 3 is also mounted to per-

mit it to be shaken or vibrated with the table rolls, a desirable form of mounting comprising horizontally arranged vibratory members 14—14 secured to table members 1—1, and vertically arranged vibratory members 15—15, on which the bearings 16—16 of the breast roll shaft 17 are mounted. An eccentric 19 is provided on shaft 11 to vibrate the breast roll, said eccentric 19 being connected by a rod 20 with a projection 21 on bearing 16, whereby rotation of shaft 11 will vibrate breast roll 3 as well as table rolls and wire, and in unison with the latter. The end of shaft 11 is supported in bearings 23—23, the other end of said shaft 70 being connected with suitable driving mechanism whereby said shaft 11 may be continuously rotated. Thus the rotation of this shaft 11 will operate the eccentrics 10 for shaking the table rolls and will also operate the eccentric 20 for shaking the breast roll, and the operation of these eccentrics will be in unison, whereby the table rolls and breast roll will be simultaneously vibrated or shaken, and will thereby vibrate the wire 4 as it passes over said table rolls and breast roll. The vibration of the rolls without the table is particularly advantageous in the present commercial machines, as they are so heavy it is hardly practical to shake the 85 whole table.

Certain subject matter of this application is disclosed and claimed broadly in copending applications of mine Serial Nos. 648,959, 648,960, 648,961, 648,962, filed July 2, 1923, 90 and 205,006 filed July 11, 1927, and hence is not so claimed in this application.

It will be understood that changes and modifications may be made without departing from the spirit of the invention.

What I claim is:

1. In a Fourdrinier machine, the combination with the table rolls, of laterally movable side rails supporting said rolls, means supporting said side rails to permit the lateral movement thereof, and means for vibrating said side rails to cause vibration of said rolls, said vibrating means comprising a rotary shaft mounted on the table and provided with eccentrics and connections between said eccentrics and one of said side rails.

2. In a Fourdrinier machine, the combination with the table and table rolls, of laterally movable side rails supporting said rolls,

- means supporting said side rails to permit the lateral movement thereof, and means for vibrating said side rails to cause vibration of said rolls, said vibrating means comprising a rotary shaft provided with eccentrics and connections between said eccentrics and one of said side rails, said rotary shaft being extended lengthwise of the table and supported by one side thereof.
- 10 3. In a Fourdrinier machine, the combination with the table, of a breast roll and means for mounting said breast roll to permit movement thereof laterally of the table, said means comprising flexible supports supporting the bearings for the breast roll shaft, and means for vibrating said breast roll comprising a rotary shaft provided with eccentrics and connections between said shaft and one of the breast roll bearings.
- 15 4. In a Fourdrinier machine, the combination with a table and table rolls, of laterally movable side rails on which the table rolls are mounted, vertically arranged upright flexible supports carrying said side rails at their upper ends and secured to the table sides at their lower ends, a breast roll having its bearings independent of the table and mounted on flexible horizontally and vertically arranged supports to permit movement of the breast roll laterally of the table, 30 and a rotary shaft extending along one side of the table and provided with eccentrics and connecting rods by which said shaft may vibrate the table roll side rails, and also the breast roll in unison. 35
5. In a Fourdrinier machine, the combination with the table, and table and breast rolls therefor, of means for mounting said rolls on the table, said means comprising vertically arranged flexible members carrying said rolls at one end and connected to the table at the other end so as to permit horizontal shaking movement of said rolls relatively to the table, and means for shaking said rolls comprising a rotary shaft provided with eccentrics connected with said table and breast rolls for horizontally vibrating the same in unison. 40 45

In witness whereof, I hereunto subscribe my name this 4th day of October, A. D. 1922.

ALONZO ALDRICH.
